Patented Aug. 11, 1970

218,338

STATIONARY EXERCISE BICYCLE

Keene P. Dimick, Santa Rosa, and Anthony J. Iozzi,
Moraga, Calif., assignors to Lifecycle, Inc., Concord,
Calif., a corporation of California

Filed Mar. 3, 1969, Ser. No. 16,013

Term of patent 14 years

Int. Cl. D21—03

U.S. Cl. D34—5

FIG. 1

FIG. 2

FIG. 3

FIG. 1 is a perspective view of a stationary exercise bicycle embodying the new design of the present invention;

FIG. 2 is an enlarged top plan view of FIG. 1;

FIG. 3 is an enlarged side elevation view of FIG. 1;

FIG. 4 is an enlarged front view of FIG. 1;

FIG. 5 is an enlarged rear view of FIG. 1.

We claim:

The ornamental design for a stationary exercise bicycle, substantially as shown.
